BUFFER

John W. Marsh, United States Army,
Washington, D. C.

Application October 28, 1942, Serial No. 463,580

2 Claims. (Cl. 213—221)

(Granted under the act of March 3, 1883, as
amended April 30, 1928; 370 O. G. 757)

The invention described herein may be manufactured and used by or for the Government for governmental purposes, without payment to me of any royalty thereon.

This invention relates to improvements in buffers for railway cars.

It is among the objects of the present invention to provide a device of the class described which is considerably simplified as to construction, assembling, inspection and repair.

Another object is to improve the operation of such buffers and to provide an arrangement of the cooperating elements which receive and absorb buffing shocks such that the danger or likelihood of damage or breakage thereof is reduced to a minimum.

These and other objects and advantages of my invention will become apparent upon a consideration of the following detailed description when taken in conjunction with the accompanying drawing, in which—

Fig. 1 is a plan view of a buffer construction embodying the improvements of the present invention;

Fig. 2 is a longitudinal cross-section along the line 2—2 of Fig. 1; and

Fig. 3 is a transverse cross-section taken generally along the line 3—3 of Fig. 2.

Referring to Fig. 1 it will be seen that there is provided a cylindrical stationary body member 10 attached to a wood block 12 which may be a portion of the car frame. The body member 10 is provided with strengthening ribs 14 extending to the rear plate 15 and is also provided with ridges 16 the top edges of which lie in a plane, thus forming a foot rest in the manner well-known in the art. Arranged for oscillating movement within the body member 10 is the buffer unit member 20 having a rounded head 18.

Referring to Figs. 2 and 3, the buffer unit 20 is provided with outwardly flaring sectors 22 spaced uniformly about the edge of the unit, preferably at 120°. There are provided on the inner surface of the member 10 shoulders 24 spaced apart a distance somewhat greater than the sectors 22. The unit 20 is placed into the member 10 by sliding any of the sectors 22 between the shoulders 24 and it is then rotated until an unflared portion of the unit is centered between the shoulders 24. This rotation places the unit 20 in a position where withdrawal is prevented by the abutment of the shoulders 24 formed by the flaring sectors 22 against the shoulders 24 of the member 10.

In order to prevent rotation of the unit 20 to the release position, there is provided a key 28, shaped to conform to the opening between the shoulders. This key 28 is inserted from the inner end of the outer cylindrical body member 10; and the inner or rearward end of the key is provided with an angularly bent portion or lip which seats in a complementarily formed recess in the adjacent end of the said member 10. This construction and arrangement limits the insertion of the key 28 to its proper longitudinal position; and also prevents its longitudinal and circumferential movement.

A spring 30 normally holds the unit 20 in its extreme forward position. A plate 32 is fitted into the rear of the member 20 and acts as a receiving plate against which the spring 30 seats. This plate 32 also contacts the lip of the elongate key and holds the same against the outer cylinder 10. The spring 30 is preferably of sufficient length so that when the plate 32 is flush with the rear of the member 10 it is under slight compression. This arrangement prevents rattling of the parts.

The parts being assembled, as above, the assembly is fastened to the block 12 by means of bolts 34 passing through openings 36 in the rear plate 15. For purposes of clarity these bolts have been removed from Fig. 3.

It will be seen that the construction just described provides a simplified buffer which consists of two castings, a spring, a key and a flat plate. Due to the fact that two-thirds of the circumference of the unit 20 is used as a shoulder surface, a spring may be used which will be strong enough to offer sufficient resistance to the shocks to which the buffer may be submitted without danger of shearing off the retaining means. The flange construction illustrated allows one-half of the surface of the unit 20 to absorb any shocks transmitted angularly to the buffer head. The large cross-section of the key 28 substantially eliminates the possibility of shearing it off by rotation imparted to the buffer head. Its installation and removal requires only the tightening or loosening of six easily accessible nuts. Since the spring is arranged to be compressed by the plate 32, the parts may be assembled without any of them under compression and the action of the nuts utilized to gain the desired operating compression.

While I have illustrated a particular embodiment of my invention, it is to be understood that I do not wish to be limited to the particular details and arrangement disclosed since various

modifications within the spirit of the invention will suggest themselves to one skilled in the art.

Having described my invention, what I claim as new and wish to secure by Letters Patent is:

1. A buffer comprising an outer cylinder, an inner cylinder slidably disposed in said outer cylinder and adapted to project therefrom, radially projecting sectors adjacent the inner end of said inner cylinder, said sectors being substantially equally spaced and extending over substantially half of the perimeter of said inner cylinder, inwardly projecting shoulders on said outer cylinder and adjacent the outer end thereof, said shoulders being substantially coextensive with the sectors aforesaid and spaced at intervals permitting the passage of the latter therebetween, a compression spring disposed in said outer cylinder, a closure member for the inner end of said outer cylinder, said spring being adapted to continuously contact said closure member and said inner cylinder whereby the latter is influenced outwardly of said outer cylinder, an elongate key disposed between certain of the inwardly projecting shoulders on said outer cylinder and the corresponding radially projecting sectors on said inner cylinder, whereby the relative rotation of the latter is prevented, said key extending into adjacency with the inner end of said outer cylinder, a radially projecting lip on the rearward end of said key, and means formed on the inner end of said outer cylinder for interlocking with said lip and thereby preventing the longitudinal and circumferential movement of said key.

2. A buffer comprising an outer cylinder, an

inner cylinder slidably disposed in said outer cylinder and adapted to project therefrom, three radially projecting sectors adjacent the inner end of said inner cylinder, said sectors being substantially equally spaced and extending over substantially half of the perimeter of said inner cylinder, said sectors being centered at substantially 120 degrees with respect to each other, three inwardly projecting shoulders on said outer cylinder and adjacent the outer end thereof, said shoulders being substantially coextensive with the sectors aforesaid and spaced at intervals permitting the passage of the latter therebetween, a compression spring disposed in said outer cylinder, a closure member for the inner end of said outer cylinder, said spring being adapted to continuously contact said closure member and said inner cylinder whereby the latter is influenced outwardly of said outer cylinder, an elongate key disposed between certain of the inwardly projecting shoulders on said outer cylinder and the corresponding radially projecting sectors on said inner cylinder whereby the relative rotation of the latter is prevented, said key extending into adjacency with the inner end of said outer cylinder, a radially projecting lip on the rearward end of said key, and means formed on the inner end of said outer cylinder for interlocking with said lip and thereby preventing the longitudinal and circumferential movement of said key, said closure member being adapted to contact said lip and hold the same against said outer cylinder.

JOHN W. MARSH.
